UNITED STATES PATENT OFFICE.

GEORGE T. HANSEN AND CHARLES F. SHERWOOD, OF SALT LAKE CITY, UTAH.

PUMP.

1,380,798.

Specification of Letters Patent. Patented June 7, 1921.

Application filed April 28, 1919. Serial No. 293,295.

To all whom it may concern:

Be it known that we, GEORGE T. HANSEN and CHARLES F. SHERWOOD, both citizens of the United States, residing at Salt Lake City, 5 in the county of Salt Lake and State of Utah, have invented a certain new and useful Improvement in Pumps, of which the following is a full, clear, concise, and exact description, reference being had to the accompanying drawings, forming a part of 10 this specification.

This invention relates to pumps.

The invention has particular reference to that class of pumps employed in pumping 15 fluids containing gritty or abrasive material. Rotary sand pumps are exemplary of this class of pumps, or as affording a still better example of a pump to which the invention is particularly applicable, reference 20 is made to the rotary pump used in pumping the "tailings" or "gangue" from ore separating apparatus. The "tailings" is the refuse left after the ore separating process has been completed and is usually composed 25 of a suspension liquid such as water and the pulverized quartz or ore from which the metalliferous particles have been extracted.

Great difficulty has been heretofore experienced in this latter type of pump, in 30 taking care of the rapid erosion of the lining in the pump casing and the surfaces of the impeller blades, which results from the rapidly moving abrasive material.

The efficiency of a rotary pump rapidly declines as the impeller blades become worn 35 from their original shape and as the clearance areas between the impeller and the casing become enlarged through the abrasion of their surfaces. We have conceived that this difficulty could be overcome or greatly relieved by protecting or rendering 40 more durable the exposed surfaces of the impeller element, as well as the exposed surfaces in the interior of the pump casing. Heretofore, it has been proposed to use 45 metallic surfaces of hard metal, such as manganese steel. But such hard metal wears away rapidly. It has also been proposed to 50 use a resilient lining for the pump casing, preferably one of rubber, such as is disclosed in the patent to Jones, No. 888,814. This resilient lining has been attended with marked success, which may be explained by 55 the fact that the rubber will yield at each point of impact before it will suffer abrasion

by the impinging particles of ore. Neither of these methods, however, make any provision for the wear of the impeller member, the practice heretofore being to substitute a new 60 impeller member for the worn one as often as necessary.

We have found that in the use of an ordinary metallic impeller with a rubber lined casing there is a tendency for particles 65 caught at the edges of the impeller to tear the rubber, and also for the abrasive particles to become embedded in the rubber and score the unyielding metallic surface of the impeller.

To maintain the original shape of the impeller, to retain the original clearance, and to prevent wear between the adjacent surfaces of the casing and impeller, we propose to apply a resilient covering over the surface of the impeller, in addition to the resilient lining in the casing. We find that two resilient surfaces subject to the flow of an abrasive material between them will possess a greater durability than two metallic 80 surfaces, or one metallic surface and one resilient surface.

We have also devised an improved method of applying the protective lining to the interior of the pump casing. This improved 85 method holds the resilient lining securely in place and facilitates the insertion and removal of the lining.

In the accompanying drawings the invention is illustrated as applied to a "tailings" 90 pump of the type above described, though, as previously stated, the invention is broadly applicable to pumps in general for pumping fluids containing abrasive material. It will also be apparent that the invention may be 95 advantageously adapted to the rotor or operating elements of different classes of machinery subject to erosion by abrasive materials, or subject to the impingement of fluids moving at high velocities.

In the drawings:

Figure 1 is a transverse sectional view through a rotary pump of the open runner type illustrating the application of the invention thereto;

Fig. 2 is an end elevational view of the same with the front half of the casing removed;

Fig. 3 is an enlarged sectional view taken on the line 3—3 of Fig. 2;

Fig. 4 is an end elevational view of a rotary pump of the closed runner type;

Fig. 5 is a sectional view taken on the line 5—5 of Fig. 4;

Fig. 6 is an enlarged sectional view taken on the line 6—6 of Fig. 4; and

5 Fig. 7 is a view illustrating the manner of protecting the inlet conduit to the rotary pump and the exposed surfaces of the valve interposed in this conduit.

Referring first to the open runner type of 10 pump illustrated in Figs. 1, 2 and 3, it will be noted that the metallic casing 2 of the pump is split into the front and rear halves 3 and 4 respectively, which are joined by bolts 5 passing through bolting flanges 6 15 and 7 extending around the circumference of the casing section. The casing as a whole is supported upon a cylindrical shaft housing 8, to which the casing is bolted, as indicated, the housing 8 comprising part of a 20 suitable pedestal bearing or the like, not shown. A bearing sleeve 9, in the cylindrical housing 8, affords a bearing for the impeller shaft 10.

The front section 3 of the casing is provided with a central intake opening 11. A 25 tailings pipe 12, leading from a separator box or other source, has communication with the central intake 11 through an elbow fitting 13 which is bolted to the tailings conduit 12 and to the front casing section 3. A discharge outlet 14 leads tangentially from the circular chamber in the interior of the casing 2, and has suitable connection with a discharge conduit 15.

35 The open runner or impeller, which is broadly designated 16, comprises a central hub 17 mounted on the driving shaft 10, and a series of impeller blades 21 radiating therefrom. The sectional formation of these impeller blades is illustrated in Fig. 3 and consists of a web portion 22 and a right angle flange 23 formed along the trailing edge of the web portion 22, as shown in Fig. 2. These flanges form pockets on the intake side 40 of the impeller blade 21, into which the pulp or tailings is delivered through the intake opening 11. The inner ends of the flanges 23 are chamfered off, as indicated, to facilitate the flow of the pulp into these pockets. 45 The centrifugal force created by the rotating impeller 16 will obviously impel the pulp outward into the annular passageway 24 from whence it will be discharged out through the discharge outlet 14.

55 The resilient lining which we employ for protecting the interior of the casing 2, is divided into two separate sections 25 and 26, each of these sections being preferably molded to conform to the interior surfaces of 60 its respective casing section. These lining sections may be attached to the interior of the casing 2 by a clamping arrangement similar to that illustrated in the Jones patent hereinbefore mentioned; or by cementing 65 to the surfaces of the casings, or by vulcan-

izing directly to the metallic surfaces of the casings. A method which we find preferable to any of these, however, is that of applying the resilient lining to a thin metallic form or backing, which has been previously pressed into the shape of the casing, the combined lining, consisting of the pressed metallic form and the resilient lining thereon, being then placed in the casing. These metallic forms are indicated at 70 and 28, and preferably consist of thin sheet steel plates which have been pressed into the conformation of their respective casing sections under a hydraulic press. A suitable grade of soft, tough rubber is the most desirable material for this resilient lining. 75 The preferred method of securing the resilient lining to the sheet steel form is to first paint the surface of the form with a vulcanizing adhesive fluid and then vulcanize 80 the rubber over this coating. The complete lining section is then fitted snugly into the casing section where it is held by the bolting together of the two casing sections.

The protective rubber covering 30, which 85 sheaths the surfaces of the impeller 16, may be applied in several ways. One preferred method is to place the impeller in a suitable mold and mold the rubber covering 30 upon the surfaces of the impeller. This method 90 possesses the advantage of always applying the same thickness of rubber upon the impeller blades so that the calculated clearance between the impeller and casing lining 95 will not vary. The rubber covering 30 is extended over the hub 17 and all surfaces of the impeller likely to be exposed to the abrasive action of the moving pulp. A vulcanizing liquid or the like may be used to assist 100 in firmly securing the rubber covering 30 over the entire area of the impeller.

Practice has demonstrated that the amount 105 of abrasion which results from the impingement of the grit particles upon the resilient surfaces, or from their frictional wear in moving across these surfaces, is practically negligible as compared with that of the hard metallic surfaces. This is due to the elasticity of the layer of rubber, which will 110 yield before it will suffer abrasion. It will be obvious from this action of the rubber surface that any particles of rock or quartz caught between the sides of the impeller and the interior of the casing will not score the surfaces but will be depressed into the 115 yielding rubber until they can work out from between the impeller and casing.

Figs. 4, 5 and 6 illustrate the invention 120 as applied to a closed runner type of rotary pump. The general construction and operation of this type of pump is substantially 125 the same as the pump just described. The pump casing 2' comprises the separable sections 3' and 4', bolted together with the circumferential bolting flanges 6' and 7'. The 13

intake is through the elbow 13' and the discharge is out through the discharge outlet 14' and conduit 15' in precisely the same manner as with the open runner type. In this case the elbow 13' is formed with an integral cover plate 32, which is bolted to a circular opening in the front casing section 3'.

The runner or impeller 33 comprises a pair of circular plates 34 and 35 spaced by a series of curved impeller blades 36. The blades 36 project laterally from the face of the rear plate 34, with which they are formed integral. This rear plate 34 is rigidly mounted upon the impeller shaft 10' and is formed with a forwardly projecting hub 37. The front plate 35 is removable from the impeller and is normally secured thereto by a spider or hollow hub 38, which projects back and is bolted to the end of the boss 37. The front plate 35 has a central opening communicating with the passageway in the elbow 13', and the member 38 has radial openings 39, affording communication between this opening and the interior of the impeller 33. Both plates 34 and 35 have openings 41 therein between the blades 36, for producing a circulation of fluid up through the clearance areas between the impeller 33 and the rubber lined casing 2'.

The rubber liner sections 25' and 26' are constructed of the pressed steel form and layer of rubber vulcanized thereto, precisely the same as hereinbefore described. The inner surface of the front cover plate 32 has an individual rubber lining consisting of the layer of rubber 42 and the pressed steel form 43 which are extensive of the rubber liner 43' and steel form 42' in the elbow 13'.

The entire surface of the plate 34 is sheathed with a protective layer of rubber 44, which extends out and also includes the surfaces of the impeller blades 36, as indicated at 45 (Fig. 6). The front plate 35 is sheathed with an individual protective layer of rubber 46 so as to permit removal of this plate from the front of the impeller 33.

We also contemplate providing the intake conduit 12 and its different fittings with our improved protective lining, as will be noted from Figs. 1 and 5. We find the use of this protective resilient lining to be of decided advantage for protecting the interior of the conduits conveying the tailings to and from the pump, and particularly for protecting the interior of the conduit at bends and elbows, and also the exposed surfaces of valves and other fittings in the conduits. In Fig. 7 we have illustrated this adaptation of our

invention as applied to the intake conduit 12' leading to the rotary pump just described. The conduit 12' is shown as comprising a plurality of conduit sections 50, preferably connected by bolting flanges 51.

The interior of each conduit section is fitted

with an individual rubber liner 52 vulcanized to a pressed steel form 53, so as to be readily removable from the conduit section. The elbow fitting 54 is similarly provided with a rubber liner 55 backed by the pressed steel form 56. It will be apparent that the outer curved surface in the elbow conduit 54 will be subject to a more severe abrasion from the impingement of the abrasive particles as they are deflected from one course of travel to another. To provide for the renewal of the resilient lining at this point without the necessity of unbolting the elbow 54 from the rest of the conduit, we have provided a removable plug 58, which seats in a boss 59 formed in the elbow 54. The plug is held in place by bolts 60 engaging in cooperating flanges 61 and 62 on the plug 58 and boss 59. The inner end of the plug 58 is curved in conformation with the curved passage in the elbow 54 and is faced with a rubber facing 63 vulcanized directly to the plug. The feature of applying a resilient pad or facing at the corner of a conduit conveying abrasive materials, is, we believe, broadly new. We contemplate the application of this idea to ash conveyors and the like.

We have illustrated a gate valve 65 interposed in the conduit 12' for throttling or completely stopping the intake flow of tailings to the pump P. The closure surfaces of a valve interposed in a conduit conveying material of this character are usually subject to a severe cutting by the impingement of the abrasive material, particularly when the valve member is in a throttling position. We have remedied this condition by facing the closure surfaces of the valve member with a resilient covering of rubber from which the impinging particles merely rebound. The valve gate 66 is of wedge formation and is arranged to fit in a corresponding wedge seat provided in the conduit passageway. A screw 67 and hand wheel 68 are arranged to raise or lower the wedge gate 66 in an obvious manner. Upon the wedge surfaces of the gate 66 we have applied a rubber facing or covering 69, which may be either vulcanized directly to the gate or mounted upon a pressed steel backing which may be suitably secured to the gate. The protective covering 69 is extended around the side edges of the gate as well, and especially around the lower edges of the gate, which are particularly subject to cutting when the gate is in throttling position. The resiliency of the rubber facing on the valve gate will always insure a tight fit in the valve seat.

The use of a resilient material for protecting the exposed metallic surfaces in the present invention, extends to all materials having the desired characteristics, such as leather, or a composition of rubber and fabric, or any other suitable material. Rubber

is the preferred material, however, owing to its greater resiliency and to the low coefficient of friction between the water and the rubber when in a wet condition. The rubber, furthermore, protects the metallic surfaces of the pump and other lined parts against the corrosive action of the acids often contained in the tailings or refuse pulp.

It will also be apparent that other methods of attaching the resilient material may be employed, such as by cement or any suitable adhesive material.

We claim:

1. In a centrifugal pump for pumping a liquid containing abrasive material, a casing having an axial inlet and a peripheral outlet, said casing being divided on a plane substantially at right angles to the axis of the pump, an impeller within the casing comprising a hub, a driving shaft secured to the hub, said impeller comprising a rigid flat portion lying in a plane at substantially right angles to the axis of the shaft, and a plurality of rigid integral flanges forming vanes and extending generally radially and lying at right angles to the flat portion, said flat portion and said flanges being completely coated with rubber secured permanently to the surfaces of the same and a removable liner of rubber having a flexible sheet metal backing fitting the interior surfaces of said casing, said liner being divided on substantially the same plane as the casing, the parts of said liner being removable laterally from the interior of the casing for repair or replacement, said impeller having its rigid portion lying between the two casing sections and partly in each.

2. In a centrifugal pump, a casing having an axial inlet, and a peripheral outlet, said casing being divided on a central plane substantially at right angles to the axis and having flanges for securing the two parts together, a lining for the interior of the pump comprising a relatively thin flexible sheet metal backing and a rubber facing, said lining covering substantially the entire interior surface of the pump casing and being divided on substantially the same plane as the casing and each half being capable of being withdrawn laterally from the corresponding casing section.

3. In a centrifugal pump, a "snail shell" casing having an axial inlet and a tangential outlet, a lining for substantially the entire inner surface of the casing, said casing being divided centrally on a plane at substantially right angles to the axis of the casing and said lining being divided into two parts on substantially the same plane, said lining comprising a thin sheet metal backing adapted to lie against the inside of the casing and a rubber facing each half of said lining having an axial tubular portion, one for an opening and the other for a shaft

opening, and each half having a tangential portion fitting the tangential outlet of the casing, said halves of the lining being held together edge to edge by the clamping together of the casing halves.

4. In a pump for pumping an abrasive material, the combination of a casing, an impeller in said casing formed of a metallic wheel structure comprising a hub, a plurality of metallic blades projecting therefrom and having impelling surfaces, said metallic blades being formed integrally with said hub, a web construction joining said blades with said hub, and a continuous covering of rubber over the outer surfaces of said blades and over said web construction for preventing the abrasion or corrosion of the metallic structure thereof.

5. In a pump for pumping an abrasive material, the combination of a casing, a closed impeller in said casing comprising a rear, circular metallic plate, a hub formed on said plate for mounting the latter on a pump shaft, a plurality of metallic impeller vanes formed integrally with said rear plate and projecting forwardly from the face thereof, a front circular metallic plate for closing off the open side of said impeller vanes, said front plate having a central admission opening for admitting the fluid to the vanes between said plates, screw means for fastening said front plate against said vanes, a protective covering of rubber molded over the exposed surfaces of said rear plate and said impeller vanes, and an independent protective covering of rubber molded over the exposed surfaces of said front plate, said latter covering being independent of the covering of rubber on said vanes and rear plate to permit removal of said front plate.

6. In a pump for pumping a fluid having an abrasive characteristic, a pump casing, said casing being divided into sections, a protective lining in said casing, said lining being divided into sections fitting into said casing sections, each section of said lining being composed of a thin sheet steel form pressed to conform to the interior of its corresponding casing section, a rubber facing of relatively greater thickness vulcanized to the surface of said form and exposed to the impingement of the abrasive material, said sheet steel form being sufficiently thin and ductile to permit of its being pressed into close engagement with the various surfaces of said pump casing.

In witness whereof I, GEORGE T. HANSEN, subscribe my name this 24th day of March, 1919.

GEORGE T. HANSEN.

In witness whereof I, CHARLES F. SHERWOOD, subscribe my name this 7 day of April, 1919.

CHARLES F. SHERWOOD.
